SPACE-BAND CLEANING MACHINE

Herbert T. Catalano, 11 Chestnut St., Franklin, Mass., assignor of twenty-five percent each to Francis N. Fournier, Seekonk, Mass., and Edgar L. Levasseur, East Providence, R.I.

Filed Aug. 13, 1962, Ser. No. 71,256

Term of patent 14 years

(Cl. D9—2)

FIG. 1 is a front elevational view of a space-band cleaning machine embodying my new design;

FIG. 2 is a top plan view thereof;

FIG. 3 is a rear elevational view thereof;

FIG. 4 is an end view thereof, looking from the left in FIG. 1; and

FIG. 5 is an end view thereof, looking from the right in FIG. 1.

I claim:

The ornamental design for a space-band cleaning machine, substantially as shown.
